(57) **CLAIM**

The ornamental design for a bite valve for a hydration reservoir, as shown and described.

DESCRIPTION

FIG. 1 is a perspective view of a bite valve for a hydration reservoir.

FIG. 2 is a second perspective view thereof.

FIG. 3 is a third perspective view thereof.

FIG. 4 is a fourth perspective view thereof.

FIG. 5 is a right side elevational view thereof.

FIG. 6 is a left side elevational view thereof.

FIG. 7 is a rear elevational view thereof.

FIG. 8 is a front elevational view thereof.

FIG. 9 is a top plan view thereof.

FIG. 10 is a bottom plan view thereof; and,

FIG. 11 is a perspective view thereof similar to FIG. 1 except showing a removable cap in place over an end of the bite valve.

The broken lines shown are included for the purpose of illustrating portions of the bite valve for a hydration reservoir and form no part of the claimed design.

1 Claim, 11 Drawing Sheets
